(57) **CLAIM**

The ornamental design for a tire tread, as shown and described.

DESCRIPTION

FIG. 1 is a perspective view of the tire tread of our design; FIG. 2 is a front elevation view of the tire tread of our design;

FIG. 3 is a side elevation view of the tire tread of our design; FIG. 4 is a side elevation view of the tire tread of our design, taken from the opposite side of that shown in FIG. 3; and, FIG. 5 is an enlarged, partial view of FIG. 1.

In the drawings, the broken line disclosure depicts environmental structure and forms no part of the claimed design. The dash-dot-dot-dash lines represent the peripheral boundary of the claim. The tread pattern is understood to repeat uniformly throughout the circumference of the tire, as shown schematically in solid lines.
